UNITED STATES PATENT OFFICE.

JAMES T. COWLEY, OF LOWELL, MASSACHUSETTS, ASSIGNOR TO THE
PLANTERS COMPRESS COMPANY, OF BOSTON, MASSACHUSETTS.

APPARATUS FOR COMPRESSING FIBROUS OR OTHER MATERIAL.

SPECIFICATION forming part of Letters Patent No. 673,860, dated May 14, 1901.

Application filed January 14, 1901. Serial No. 43,093. (No model.)

To all whom it may concern:

Be it known that I, JAMES T. COWLEY, a citizen of the United States, residing at Lowell, in the county of Middlesex and State of Massachusetts, have invented a new and useful Apparatus for Compressing Fibrous or other Material, of which the following is a specification.

This invention relates to apparatus for compressing fibrous or other material and is designed as an improvement upon the construction shown, described, and claimed in Patent No. 653,735, issued July 17, 1900, to Watson M. Holmes.

The object of the invention is to improve the construction and arrangement of the slotted head-plate or cap, whereby the bridging of the material from one slot across to another is avoided, and to avoid the formation of a hard knot or core at the center of the bale.

Other objects of the invention will appear more fully hereinafter.

The invention consists, substantially, in the construction, combination, location, and arrangement, all as will be more fully herein-after set forth, as shown in the accompanying drawings, and finally pointed out in the appended claims.

Referring to the accompanying drawings and to the various views and reference-signs appearing thereon, Figure 1 is a fragmentary plan view of a head-plate ring and head-plate, showing the arrangement and location of the feed-slots through such head-plate. Fig. 2 is a section on the line 2 2, Fig. 1.

In Patent No. 630,374, issued August 8, 1899, to George A. Lowry, is disclosed a construction of press for compressing fibrous and other material in which is employed a slotted head-plate or cap mounted for relative movement with respect to the compressed material. In the operation of a baling apparatus embodying these generic features, by imparting a relative movement to the slotted head-plate or cap and the compressed material and supplying additional material to be compressed to or adjacent to the slot or slots in the cap or head-plate such material is caught or engaged by the material previously introduced through

such slots and is drawn through the slot or 50 slots and compressed and formed into condensed thin sheets or spiral layers, the body of the compressed material being augmented endwise by each spiral layer thus added thereto and correspondingly advanced or lengthened in the form of a column in a highly compressed or condensed state. It is set forth in said patent that the feed-slots therein shown and described terminate a short distance from the geometric center of the cap. In the practical operation of such construction it has been developed that in compressing fibrous or other material, and particularly material of long fibers, it sometimes occurs that the fiber will be caught at one end in one slot and at 65 the other end in an adjacent slot. This occurs more particularly at the inner ends or slots where adjacent slots come in close relation to each other. This bridging action of the material from one slot to another results 70 in the formation of a hard lump in the center and frequently obstructs materially the feeding capacity of the slots. In the patent to Holmes, No. 653,735, above mentioned, it was sought to avoid this objection by forming the slots so as to be continuously open to 75 the center of the cap, the inner end of each slot communicating or opening into the inner end of each of the other slots. By this construction it was found that when the fibers 80 of the material are engaged by the compressed material and drawn through one of the feed-slots in the head-plate or cap and a tendency is developed of such fiber to be also engaged or drawn through an adjacent slot 85 such material will gradually work toward the center during the operation of the machine, and by reason of this center being open—that is, by reason of the slots opening into each other at the center of the cap-plate, as 90 above indicated—such material slides over the projections of the cap which forms the bounding edges of the slots at their junction at the center of the cap or head-plate without unduly obstructing the feeding capacity 95 of the slot or slots or the operation of the machine. It has been found in practice, however, that while such construction avoided the ob-

jection of bridging of the material over the head-plate or cap, or that portion thereof lying between adjacent slots, by reason of the fibers being engaged at one end in one slot and at 5 the other end in an adjacent slot, another objection is encountered—namely, the forming of a hard core or knot at the center of the bale, due to the location of the common junction of the slots at the axial center of the 10 head-plate or cap and the consequent crowding in at this point of more than the necessary or required amount of material. It is the special purpose of the present invention to overcome this objection, and this result is 15 accomplished by forming the common junction of the feed-slots at their inner ends at a point offset from the geometric center of the head-plate or cap.

Referring to the accompanying drawings, 20 in which is illustrated a feed-cap or head-plate constructed in accordance with the principles of my invention, reference-sign A designates the head-plate ring, upon which is supported the head-plate. This head-plate 25 may be of any suitable or convenient construction and provided with feed slots or openings therethrough, reference-signs 1, 2, 3, and 4 designating such feed-slots. In the particular form shown, to which, however, the invention 30 is not to be limited or restricted, the head-plate is composed of sections A', which may be firmly bolted or otherwise secured to or formed with the head-plate ring A and which sections are suitably offset from each other at 35 their edges to form the feed-openings 1, 2, 3, and 4. Any desired number of feed-slots may be formed through the head-plate, and while I have shown four of such feed-slots I do not desire my invention limited to the exact number shown. The intersection of the dotted 40 lines 6 7 indicates the geometric center of the bale and of the head-plate or cap. This intersection is designated by reference-sign 5. It will be seen that in the form shown this 45 point is located close to one side of one of the slots and that the point of common junction of the slots is offset from this point 5. I have above indicated that relative movement is imparted to the head-plate or cap and the column of compressed material.

In the particular form shown, to which the invention is not limited, it is designed to relatively rotate the slotted head-plate or cap and the column of compressed material. Therefore by the offsetting of the point of juncture of the inner ends of the slot from the axial center of the compressed column it will be readily seen that any material which might bulge up at the junction of the inner ends of 55 the slots would during the relative rotation of the head-plate or cap and the compressed column of material be carried around the center by reason of such relative rotations, and consequently would be ironed down at each revolution by the projection 8 of the head-plate,

which forms a bounding edge of the junction of the inner ends of the slots.

I do not desire to be confined to the exact location of the junction of the slots with reference to the axial center of relative rotation 70 of the compressed column and slotted head-plate or cap so long as such point of junction is offset from such axial center.

As above indicated, I do not desire to be limited to the exact number of slots in the 75 head-plate or cap. For instance, slots 1 and 2 may be omitted, in which event the dotted line 9 would designate the bounding-surface at the junction of slots 3 and 4. Similarly, if slots 3 and 4 were omitted the dotted line 10 80 would designate the bounding-line of the junction of slots 1 and 2. In either case the effect would be the same, as the geometric axis of relative rotation of the compressed column and the head-plate or cap would be offset from 85 the juncture of the slots, and hence would be covered up by an overlying portion of the head-plate, and consequently any bulging of the material occurring at the junction of the slots during the relative rotation of the column and cap or head-plate would be ironed or smoothed down, thus avoiding the objection of the formation of hard cores or knots at the center of the compressed column.

It is obvious that the principles of my invention may be applied to the case where the compressed column is held stationary and the head-plate or cap revolves relative thereto, and also equally well to the case where the cap is stationary and the compressed column 90 revolves or where both the compressed column and the cap revolve, but in opposite directions.

In Fig. 2 a compression sleeve or chamber B is employed; but this feature is not essential and may be omitted, if desired.

Having now set forth the object and nature of my invention and a construction embodying the principles thereof, what I claim as new and useful and of my own invention, and desire to secure by Letters Patent of the United States, is—

1. In a machine of the class described, a head-plate or cap having slots or openings therethrough, said slots forming a junction with each other at their inner ends, the point of junction being offset from the center of such head-plate or cap, as and for the purpose set forth.

2. In a machine of the class described, a head-plate or cap composed of sections, said sections being offset edge to edge to form slots or openings therebetween, said slots or openings forming a junction with each other at their inner ends, the point of junction of such slots being offset with respect to the 115 geometric center of said head-plate, as and for the purpose set forth.

3. In an apparatus for compressing fibrous or other material, a head-plate having feed-slots, means for relatively rotating said head- 130

plate and the compressed material, the feed-slots in said head-plate forming a junction with each other at their inner ends, said point of junction being offset with respect to the axis of such relative rotation, as and for the purpose set forth.

In witness whereof I have hereunto set my

hand, this 8th day of January, 1901, in the presence of the subscribing witnesses.

JAMES T. COWLEY.
